METHOD OF FINISHING SHORTENING

Truman M. Godfrey, Winchester, Mass., and Victor Serbell, Leonia, N. J., assignors to Lever Brothers Company, a corporation of Maine

Application May 5, 1937, Serial No. 140,826

14 Claims. (Cl. 99—122)

This invention relates to a method of finishing a substantially dry plastic shortening.

More particularly, the invention relates to the processing of shortening to improve its texture, plasticity and appearance and to impart more desirable culinary properties, for example, large creaming volume, improved baking quality, and increased shortening power.

There are several general types of plastic shortenings. One type is the so-called compound type which is made from edible liquid oils blended with a sufficient portion of solid fat to give the final blended product the desired plasticity. Another general type is made up primarily of oleaginous material of a desired plasticity. This may be either naturally occurring oleaginous material or oils or blends of oils which have been treated so as to produce the desired plasticity, for example, by hydrogenating oil or blends of oils. If desired, this plastic oleaginous material may be blended with fats and/or oils. This invention is applicable to any of these types of shortening.

In preparing shortenings, the preliminary refining and bleaching of the oil or fat, the hydrogenation of the oil, if this step is included, the blending, deodorization, etc., are carried out when the oil is in a liquid state and usually at an elevated temperature. After these processing steps are completed it is customary to cool or chill the oil so that it is converted into a plastic or semi-solid condition. It may be aerated and subjected to further treatment for improving its physical and culinary properties.

The chilling and subsequent treatment is termed "finishing" and it is to this portion of shortening manufacture that the invention relates.

The treatment to which the shortening is subjected after the chilling has heretofore largely been determined empirically without an understanding of the exact effect of the various steps on the physical and culinary properties of the product. As a result of the study which led to the invention, the various factors which influence the texture, appearance and culinary properties are now better understood. New treatments have been discovered which greatly improve the shortening and the process of the invention employs these new treatments together with those steps of the previous processes which are now known to improve the shortening. Those steps previously employed which have no effect of improving the shortening, or a deleterious effect, are not employed.

The invention, in addition to some of the steps ordinarily employed in shortening manufacture, includes the following steps: pre-cooling or "seeding" the liquid oleaginous material immediately after or before the introduction of air or any other gas, agitating and shock chilling the oleaginous material while removing only sufficient latent heat of fusion to prevent the final temperature from exceeding a predetermined tempering temperature, or temperature of normal usage, packing the product at the proper consistency and temperature, after it has been previously double or triple expanded and texturated, and storing the product from one to six days at the tempering temperature before use in order that the structure of the product may reach an equilibrium along with maximum plasticity.

Before the invention is described in detail or its objects pointed out with more particularity, it is desirable to consider the effect of shortening in a baked flour product and some of the desirable properties a shortening should have. The action of shortening in a flour product is physical rather than chemical, and therefore the physical properties of the shortening are particularly important.

Flour is composed of 70-75% starch in the form of granules which remain as solid particles throughout the process of mixing and baking. The proteins contained in flour are principally glutenin and gliadin, both of which absorb water. The gliadin forms with water a glue-like mass which comes in contact with the firmer particles of glutenin during the mixing and forms the gluten of the dough. The gluten exists as strands and layers throughout the dough mass and as the mixing is continued, these strands of gluten come in contact with each other and stick together. In this way, the gluten develops and becomes stronger and more coherent. The network of gluten forms the skeleton of the dough and in this network the starch granules are held. If such a dough were baked without shortening, a hard, strong product would be produced which could not be easily broken or crushed.

From this consideration, the fundamental action of shortening can be more easily understood. On mixing a shortening with the dough, the shortening is mingled very intimately with other ingredients, although it remains distinct and does not dissolve. During the mixing, the shortening spreads and coats fresh surfaces in the dough. When a fibre of gluten tends to come in contact with another fibre of gluten, the intermediate

film of shortening prevents these two fibres from cohering as intimately as they otherwise would. In a like manner, the shortening also penetrates between the starch granules. The shortening, therefore, breaks up what otherwise would be a continuous mass in the dough and performs the function of a separator or lubricant for the constituents of the dough. The various flour particles which are covered with the shortening do not adhere tenaciously to each other at their point of contact because of the shortening, and hence the product tends to crumble or break and in this condition it is denoted as being tender or "short".

15 It is well known that some shortenings have much greater "shortening power" per pound than others. This is due to a number of features, some of which are not fully understood inasmuch as the dough is a very complex mixture of colloids 20 partially in colloidal solution and partially in suspension, and the introduction of the shortening in the dough brings about complicated changes in the structure.

25 One of the most important properties of a shortening is its even plasticity, smoothness and fineness throughout the mixing. If the shortening is liquid or too soft, or contains a large proportion of liquid ingredients available as such, the shortening may be absorbed by the starch 30 granules to a considerable extent and as a result, the dough will be "soggy". The shortening in such a form may even separate from the dough and collect in small isolated pools and the distribution of the shortening throughout the dough 35 therefore will not be uniform.

40 A shortening also cannot be too hard, or non-plastic, because then it cannot coat or completely envelop each of the starch granules or spread uniformly and intimately throughout the dough 45 mass. A shortening which is too hard or non-plastic will not cover as great an amount of surface and will not fill in all the cracks, pores and spaces in the dough.

45 It will be seen, therefore, that a shortening which remains plastic throughout the mixing will have a much greater "shortening power" than one which is either too solid or too liquid. The oleaginous material which comprises the shortening is generally a mixture of different oils 50 and different fatty compounds having different melting points. Prior to the finishing operation, the various oils and fats comprised in the shortening are blended in such proportions that the final product, when properly finished, will 55 have the desired plasticity.

60 For reasons mentioned previously, it is desirable that the shortening should have uniform plasticity. To accomplish this, it is necessary that the liquid oils in the shortening should be distributed in extremely minute particles throughout the solid fat so that the finished product becomes a matrix of solid fat through 65 which the liquid material is uniformly and finely distributed. The liquid oils when in this condition, impart the desired plasticity to the shortening but are not readily available for deleteriously affecting the baked product.

70 It is therefore an object of the invention to provide a shortening in which the liquid oil is distributed in minute quantities or particles in a fine matrix or crystal network of solid fat, so that the liquid constituent is not present as such in large particles in the shortening.

75 The amount of shortness or tenderness in a baked product is in general a function of the pro-

portion of shortening in the product and this amount is determined by the character of product desired; too short a product will crumble or break readily and is not as preferable as a product which has sufficient mechanical strength to retain its shape and structure under handling and shipping conditions.

80 The ultimate criterion of the culinary properties of a shortening is its ability to impart to the final baked product a maximum lightness with a given desirable degree of tenderness. In any given flour product it is desirable to obtain the greatest volume possible because this produces a maximum lightness in the product. The shortening, therefore, which has the best baking 10 qualities is one which, when employed in an amount to give a predetermined tenderness, i. e., employed in a given ratio to each of the other ingredients of the product, will produce a product having the maximum volume.

15 A test suitable for determining the baking qualities of a shortening is the pound cake test in which given quantities of ingredients are employed and mixed under standard conditions and in accordance with a standard procedure. 25 Shortenings finished by different processes when employed under such standard conditions will produce products having different textures and volumes and the shortening which produces a product having the lightest texture is said to 30 have the best baking qualities.

35 It is an object of the invention to produce a shortening having excellent baking qualities; i. e., the properties of imparting a large volume to the baked product.

40 Another culinary property often referred to in connection with shortening is its creaming quality. By creaming is usually meant the ability of the shortening to form a light, fluffy mixture when it is beaten with other ingredients, usually sugar, and the ability of forming a mixture which holds air bubbles and increases in volume and acquires a smooth texture.

45 The creaming quality of a shortening has no direct relation to the baking quality, inasmuch as a shortening which creams well may not produce a final product having as large a volume as a shortening which does not cream so well; there is no ultimate merit in a shortening merely because it creams well if it does not produce a 50 final product having a large volume and light texture. However, the housewife, cooks and bakers have, over a long period of time, been educated to demand a shortening which creams well, and there is the general belief that in order 55 to produce a desirable flour product, it is necessary to have a shortening which creams well.

60 In view of this understanding in the art, it is an additional object of the invention to provide a shortening which, in addition to having excellent baking qualities also has good creaming qualities.

65 A factor in obtaining a desired creaming quality is the incorporation of a gas such as air, nitrogen or other inert gas into the plastic shortening. The gas is preferably distributed in the form of very minute bubbles and is usually referred to as being "occluded". The smaller the bubbles and the more uniform their distribution, the better is the appearance and creaming qualities of the shortening. Many difficulties are encountered in incorporating the air in the desired finely divided condition, particularly if the shortening is not of the proper plasticity at the time and 70 75

under the conditions in which the air is incorporated.

It is an object of the invention to incorporate a gas while the shortening is in a condition most suitable for its reception, distribution and retention, and by means of the invention a finer and more uniform distribution of the gas can be obtained. It has been found, in addition to other factors also considered, that the incorporation of the gas can be desirably assisted by introducing it into the shortening under pressure.

It is also an object of the invention to add a gas under pressure while the shortening is in a closed receptacle, so that inert gases, for example, nitrogen or carbon dioxide, may be incorporated, if desired, without dilution.

The characteristics of shortening may be modified, for example, as to solidifying temperatures as well as to others by suitable selection and blending of the various oils available. Shortening may be manufactured from a variety of vegetable oils, such as for example, cottonseed, corn, kapok, sesame, peanut, cocoanut, palm kernel, and others. These oils may be mixed in various proportions depending upon their availability, the type of shortening desired, and the season at which the shortening is manufactured and distributed as well as other factors.

The temperature ranges maintained at various stages of the finishing operations as well as the temperature of the shortening itself depend primarily upon the characteristics of the final product desired, which characteristics are in turn influenced by the composition or blend of oils making up the shortening, the season of the year in which the fat is made or marketed, and the use to which the product is particularly adapted. For these reasons, it is difficult to assign any definite temperature or temperature range to the various phases of the operation. However, in order to better describe the invention and to distinguish it more fully from prior processes, temperature ranges are included which cover many of the types of products to which the invention relates. However, temperatures outside these ranges are not necessarily to be excluded because in some instances certain desired products may require, in the processing, temperatures outside these ranges.

In order to convert the oleaginous material in a liquid state into a semi-solid condition, the usual practice in accordance with the methods of the prior art has been to apply the liquid material to a refrigerated revolving roll. The liquid material partially solidifies in a thin film on the surface as the chilled roll revolves. Near the end of a revolution of the roll the semi-solid fat is scraped from the roll. It has been customary to aerate the fat by heating air into it, for example in a so-called "picker-box". In order that the requisite amount of air may be beaten into the fat by such an operation, the fat should be in a plastic state. If the fat is too soft when it is removed from the chill roll, the air cannot be incorporated by the beating. For this reason the fat is usually kept on the chill roll long enough to be sufficiently solidified for aerating by beating. During the chilling operation a large portion of the latent heat, which is developed as a result of the change in the shortening from a liquid to a solid condition, will have been absorbed by the refrigerated roll. Not all of the latent heat is absorbed in this manner, however, and during the beating operation in the picker-box, the remaining small portion of the latent heat is ab-

sorbed by the shortening and the temperature rises.

In the chill roll operation of the prior art, the fat removed from the chill roll usually has a temperature of about 9 to 12° C. After the remaining latent heat is absorbed, the shortening in the picker-box rises to a temperature of about 19 to 22° C.

It has been discovered that if after the chilling and aerating, the finished product is stored from one to six days at a temperature of about 25 to 30° C., the baking quality of the shortening is materially improved as compared with the shortening which is not "tempered" at about this temperature. For example, a shortening which is packed and retained at about 20 to 22° C. will have decidedly inferior baking quality as compared with a shortening which is otherwise identical but which has been packed and stored at a temperature of 26 to 30° C. for from one to six days.

If the product is packed at a lower temperature, for example at the temperature in the picker-box, and placed in a storage chamber maintained at the higher tempering temperature, it will take a considerable time for the product to acquire the tempering temperature because of the low temperature differential between the shortening and the storage chamber. This will be especially true if the shortening is packed in large containers. It may take several days for all of the shortening in the container to reach the tempering temperature.

In order to decrease the time necessary for the tempering, it is desirable to pack the shortening at approximately the temperature temperature. As has been pointed out previously, fat which has been chilled on a chill roll has had such a large portion of the latent heat extracted by the chill roll that the latent heat remaining is not sufficient to raise the temperature of the product to a packing temperature which approximates the tempering temperature. In order to avoid this difficulty it has heretofore been proposed to heat the shortening after it has been aerated in the picker-box, in order that the fat may have a packing temperature which is near the desired tempering temperature. This heating of the shortening is exceedingly difficult to accomplish without materially impairing the desired properties, because heat applied to any portion tends to melt the fat, especially those oils which have been shock chilled. The result is that the melted portion takes on a greasy, vaseline-like appearance due to the release of the occluded air from the melted portion.

If the heated shortening is then agitated the melted fat is mixed with the solid fat with the result that the entire product takes on the yellowish cast characteristic of a vaseline-like appearance.

Numerous modifications of the heating operation have been proposed in order to heat the shortening more uniformly without any local overheating, but such modifications are commercially undesirable. At first consideration it would appear that the problem could be solved by permitting the oil to remain on the refrigerated chill roll for a shorter length of time so that less latent heat is extracted by the roll and sufficient latent heat remains to cause the temperature of the product in the picker-box to rise to a point where it approximates the desired tempering temperature. However, if the chill roll is operated in such a manner, the fat re-

moved therefrom will be so soft that it will be impossible to beat the desired amount of air into the fat at atmospheric pressure by the usual operations.

5 It is an object of the invention to chill the fat in a manner such that during the subsequent finishing operations, it is not necessary to add external heat in order that the shortening will have a packing temperature which approximates the tempering temperature.

10 By "tempering temperature" is meant a pre-determined temperature at which shortening is stored from one to six days or longer, immediately after being packed, in order to maintain the

15 fat at a sufficiently high energy level to cause a crystal arrangement to take place in the shortening which improves its baking properties, appearance, texture, stability and plasticity. It has also been found that this tempering temperature is the proper creaming and mixing temperature.

20 In most of the products this temperature will be between 25 to 31° C. and in many cases the temperature is about 27 to 28° C. However, certain particular products stored at a tempering temperature outside this range may have their baking

25 qualities improved.

In accordance with the invention, the liquid oleaginous material is first pre-cooled by passing it through a pre-cooler; it is then chilled by

30 passing it through a refrigerated chilling device in which it is constantly maintained in a state of vigorous agitation.

35 Before referring to the pre-cooling operation in detail, it is well to note that prior to the chilling operation, the oil is stored at a temperature at which no crystallization will take place. This temperature varies with different oils but is usually above 45° C. and in most instances is above 50° C. Therefore in cooling the oil from 40 this temperature, partially solidifying it and packing at the preferred temperature, there is a considerable quantity of sensible heat, as well as some latent heat of crystallization, in the oil which must be transferred to the cooling medium. If the oil at the storage temperature is introduced directly into the agitated chilling device all of this both sensible and latent, must be absorbed by the refrigerated surface.

45 In the pre-cooling operation the temperature of the liquid oleaginous material is lowered sufficiently to permit the formation of a large number of nuclei crystallizing centers in the material before it is chilled, in which operation the crystalline structure of the plastic shortening develops around these nuclei centers. As a result, the total amount of heat that must be absorbed during the chilling operation is decreased and the capacity of the chilling device is increased.

50 It has been found that the rate of solidification of the oleaginous material largely determines the grain and particle size of the fat crystals. The faster the rate of crystallization the smaller is the size of the fat crystals. The smaller the particle size the better will be the texture, appearance, plasticity, baking and creaming properties of the shortening. Therefore, a fast rate of solidification is desirable.

55 The rate of solidification, and hence the crystalline structure of the fat, is dependent upon the number of nuclei crystallizing centers existing in the material per unit volume at the time of solidification. It is therefore desirable to pre-cool the material so as to form the maximum number of nuclei crystallizing centers.

75 The formation of the nuclei centers in the

case of fats is dependent upon the temperature to which the fat is pre-cooled, and also upon the time interval allowed. In fact, a greater concentration of nuclei centers is formed when there is a limited amount of pre-cooling as compared with excessive pre-cooling. The extent of the pre-cooling and the time the oleaginous material is permitted to remain in the pre-cooler is so regulated that the maximum number of nuclei centers is formed in the fat before it is passed to the chilling device, and therefore in the chilling operation the rate of solidification proceeds at the maximum rate.

10 In the pre-cooling operation the liquid oleaginous material enters a pre-cooling chamber and comes in contact or mixes with material that has previously been pre-cooled and partially grained or formed with nuclei crystallizing centers. The pre-cooling operation permits this "seeding" to take place during a definite time interval, an operation that would be impossible if the fat were suddenly chilled.

15 The pre-cooling of the fat so as to permit the formation of a large number of nuclei centers before chilling is distinctly different from the operations in accordance with the prior art, for example with the chill roll the warm liquid oil is passed directly to the chilling device. In such prior processes the fat is rapidly cooled below the temperature at which the maximum number 20 of nuclei centers may be formed, so as to materially decrease the formation of the crystallizing centers and in turn decrease the rate of solidification.

25 In the operations in accordance with the prior art a considerable portion of the time, during which the oleaginous material is in contact with the refrigerated surface of the chilling device, is utilized in reducing the energy level of the fat to a point where it may solidify. This time is 30 not available for solidification of the oleaginous material and, therefore, the capacity of the device is decreased to that extent.

35 The pre-cooled oleaginous material is then subjected to a refrigerated surface under agitation, whereby each particle of the oil that contacts the cold surface is chilled, and then removed or scraped from the cold surface and replaced by another particle of oil. Due to the vigorous agitation all of the particles of the oil 40 are subjected to the cold surface and the oil as a whole is uniformly and thoroughly chilled. The contact of each particle of the oil with the chilled surface is so short that there is little opportunity for the latent heat developed by the change of state or solidification to be absorbed by the cold surface, and the latent heat that it developed during the solidification is absorbed by the body of the shortening rather than the chilled surface. The fact that the fat is thoroughly and 45 uniformly contacted with the cold surface so that the fat is thoroughly chilled is not apparent because the latent heat has been absorbed by the shortening after the chilling rather than by the refrigerated surface. As a result, the fat after 50 the chilling operation, will have a higher temperature than a corresponding fat removed from a chill roll. For example, the fat immediately after it has been chilled by the process may have a temperature of from 13 to 18° C. as compared 55 with the temperature of 9 to 12° C. in the chill roll operation. This is due to the fact that a portion of the latent heat has been absorbed by the fat while in the agitated chilling device. The fat, after it leaves the chilling device, still 75

contains enough latent heat so that during the finishing operations subsequent to the chilling, the temperature will be raised to the packing temperature which, in most instances, approximates a tempering temperature.

As a matter of fact, the rate at which the latent heat is absorbed by the chilled surface in our chilling process is so low as compared with the chill roll process that it is readily possible to remove the shortening from the agitated chilling device before the desired amount of latent heat has been absorbed by the chilled surface, in which case, due to the excess of latent heat the fat will have a final temperature higher than the packing or tempering temperature. In order to assure that the final temperature is not too high, it is essential that the fat remain in the agitated chilling device long enough to absorb the necessary amount of latent heat.

The pre-cooling operation prior to the chilling is not necessary and the process can be practiced by introducing the oil directly into the agitated chilling device. However, the capacity of the chilling device is somewhat decreased, due to the fact that the first part of the chilling device must perform the function of the pre-cooler and the rate at which the fat can be chilled is much lower. When the pre-cooling operation is not employed the nuclei crystal centers do not have as long a time in which to form and the crystalline structure of the finished fat, while decidedly superior to that obtainable with the chilled roll, is not as desirable as that obtained by pre-cooling.

It has been pointed out heretofore that the solid portion of the shortening consists essentially of crystals of solid fat within which the softer and liquid portions are held, and that the nature of these crystals, their size and amount, as well as the manner in which they are formed and inter-connected, largely determines the baking qualities of the shortening, the plasticity, and the temperature range over which this plasticity is retained.

In the chill roll type of operation, the crystalline structure of the solidified fat is bound to be very heterogeneous because of the uneven chilling of the fat on the roll. That portion of the layer of fat which contacts the roll is thoroughly chilled, but this is the only portion which is completely chilled, because this chilled portion acts as an insulator and protects the upper or remaining portion of the layer from the action of the chilled surface so that this portion is not chilled to the same extent. It will, therefore, be seen that a different crystalline structure will be formed in different portions of the layer of fat. In the process of the invention, due to the agitation during the chilling, the crystalline structure of the entire mass of fat will be more uniform.

In the chill roll type of operation, the fat is also permitted to remain motionless on the roll for a considerable length of time, for example, 7 to 10 seconds. During this relatively long period of time, the undisturbed crystals in the fat have an opportunity to grow and become relatively large. The chilled fat, therefore, has a coarse crystalline structure which retains the liquid phase of the shortening in a less finely distributed condition, with the result that the shortening is oily or greasy. In addition, this coarse network of large crystals causes the product to be hard and lacking in plasticity. In accordance with the invention, due to the agitation to which the shortening is being continuously subjected during the chilling and other subsequent operations, the

crystalline growth is very fine and the crystals are small, with the result that the liquid phase of the shortening is held in a more uniformly and finely distributed condition and the shortening has the qualities of a solid fat while at the same time being more plastic.

The investigations leading to the invention have shown that two of the important elements in a process of finishing shortening which has good baking qualities are the proper chilling of the fat and the tempering of the shortening after it is packed.

The proper chilling is requisite for the formation of the proper crystalline structure in the shortening; this also converts all of the oils in the shortening which may be solidified into a solid form. As illustrative of the effect of complete chilling it has been observed that fat which has been thoroughly and completely chilled without any subsequent treatment has excellent baking properties. However, the finishing operations subsequent to the chilling for imparting a more uniform and desirable texture and appearance to the shortening, do not improve its baking qualities and in some instances render the baking qualities inferior to those possessed by the fat immediately after chilling. It has already been pointed out that a tempered shortening has superior baking properties as compared with a shortening which is not tempered after packing.

The process, therefore, in addition to including many other desirable steps, is particularly adapted to accomplish, in a thorough and efficient manner, those two steps which increase the baking qualities to the greatest extent, namely, chilling and tempering.

An apparatus in which the process can be practiced is illustrated in the accompanying drawing which forms a part of the specification. In accordance with an example of the process described here merely as illustrative, the treated oil is withdrawn from a storage tank at a temperature of about 45 to 55° C. through the pipe 1 into a small storage tank 2 which is employed in order to have an ample and constant supply of oil near the chilling apparatus. The level in this storage tank is maintained by a valve 3 operated by float 4. The oil is withdrawn from the storage tank 2 by a pump 5 operated by any suitable means, such as a motor 6. The oil passes through a pipe 7 to a pre-cooler indicated generally at P. The pre-cooler may consist of a number of parallel tubes 8 which connect two headers 9, and through which cooling water passes by means of suitable inlets and outlets 10 and 11. The extent to which the oil is pre-cooled depends upon and may be controlled by the temperature and the amount of cooling water passed through the pre-cooler.

The oil is then passed through a pipe 12 to the agitated chilling unit, generally indicated at A. This may comprise a tube 13 through which the fat passes. The tube 13 is surrounded by a refrigerating medium, such as ammonia, which may be introduced through convenient inlets and outlets 14 and 15. The length of the tube and its diameter may be varied, depending upon the capacity of the fat it is desired to chill and the extent of the chilling desired. Extending through the center of the tube 13 is a central shaft 16 which is rotated by any convenient source of power, such as the drive 18. Attached to the shaft 16 are the blades 19; the blades may overlap each other and are preferably loosely mounted on the shaft so that upon the rotation of the

shaft, the blades are rotated and forced outwardly and in contact with the interior walls of a chilling tube 13. The shaft is rotated at a relatively rapid speed, for example, about 1,000 5 R. P. M.; the oil and fat is violently agitated within the tube and the blades continually remove or scrape the fat from the inner walls of the tube as soon as it is chilled. The pump 5 maintains the fat under a comparatively low 10 pressure, for example 25 to 75 lbs., during the pre-cooling and chilling operations.

The pre-cooler having absorbed a part of the heat, the remainder of the sensible heat is absorbed by the chilling unit together with a part 15 of the latent heat of crystallization. An additional portion of the latent heat is absorbed by the fat while it is in the tube 13 and the remaining portion of the latent heat is absorbed by the shortening after it leaves the chilling unit. After 20 the fat has absorbed all of the latent heat it will have a temperature approximating the packing temperature.

The temperature of the shortening as it leaves the unit A will vary depending on the oils and 25 fats used, and the temperature at which the shortening is to be packed; in general the temperature will be about 13 to 18° C.

Air or a suitable inert gas may be introduced 30 into the oil through a pipe 20. If an inert gas, such as nitrogen or carbon dioxide, is employed it can be introduced from a tank 21; the amount of gas to be introduced can be regulated by means of the valve 22.

The air or inert gas is preferably introduced 35 into the oleaginous material while it is in a liquid state. This introduction of the gas also preferably takes place before the material is passed into the pre-cooler, for example, on the suction side of the pump 5. Under these conditions the 40 air or inert gas is dissolved and occluded in the material.

The pressure applied to the liquid oleaginous material as it emerges from the pump 5 into the pre-cooler is such that the fat will dissolve at 45 least a large portion of the air or inert gas. In as much as the shortening remains under a pressure in excess of atmospheric pressure until it passes through the last agitating device, a great portion of the introduced air or inert gas will 50 be present in the dissolved form until a point is reached in the process where the shortening is subjected to atmospheric pressure.

This procedure has been found to be advantageous 55 because the capacity of the pre-cooler and the chilling device is increased due to the fact that a portion of the effective heat transfer surface is not occupied by occluded gas. Furthermore, when the shortening is restored to atmospheric pressure, the gas which was dissolved 60 under pressure passes into the occluded state in much smaller globules than would be possible if the fat were chilled in the presence of occluded gas.

If all of the air or inert gas is not dissolved 65 prior to the chilling operation the undissolved portion of the air or inert gas will be uniformly and finely occluded during the chilling operation due to the vigorous agitation.

As has been pointed out before, a soft fat or 70 oil cannot have air occluded therein at atmospheric pressure by a picked-box beating operation. However, under the pressure maintained in the pre-cooler and the chilling device air or inert gas may be dissolved and occluded in the 75 relatively liquid oil and soft fat.

If desired, the air or inert gas may be introduced at other points in the process prior to the chilling, for example, subsequent to the pre-cooling operation.

As the shortening exists from the chilling unit 5 it is introduced into a high pressure pump 23, operated by a suitable source of power, such as the motor 24. The pump places the shortening under a relatively high pressure, for example 300 to 500 pounds per square inch. The shortening 10 then passes through an agitating device, generally indicated at B, consisting preferably of a closed tube through the center of which is a shaft 26. Mounted on the shaft are paddles or blades 27 for mixing and agitating the fat as it passes 15 through the device under the high pressure maintained by the pump 23. The shaft may be operated by any convenient source of power applied to the wheel 28.

As a result of the agitation during the chilling, 20 the shortening will be very uniform in texture when it enters the unit B. As it is mixed or agitated under pressure in the unit B, it is further smoothed and the air is distributed more uniformly. The maintenance of the fat under 25 pressure in this mixing operation imparts a better appearance and texture to the shortening. The exact effect of the pressure is not known, but because the small bubbles of air or inert gas 30 occluded in the fat are under great pressure and are very small, it is possible that the small compressed bubbles are distributed more uniformly than larger uncompressed bubbles of air or inert gas. In addition, it is probable that under pressure the fat softens at a lower temperature or 35 vice versa becomes softer at the same temperature when placed under pressure.

As the fat moves through the unit B, some 40 of the remaining portion of the latent heat not absorbed in the chilling unit A will be here absorbed by the shortening, and as a result, the temperature of the shortening may increase about 4 or 5° so that as it leaves the unit B it may have a temperature of from about 17 to 23° C.

The shortening is then passed through a texturizing valve 29 which consists of a relatively small slit or orifice through which the fat is passed under the high pressure maintained by the pump 23 and released into a zone of substantially atmospheric pressure. As the shortening 50 passes through this orifice, it is expanded and acquires a more uniform texture and appearance as well as a greater plasticity. Any lumps which may be in the shortening are smoothed out as they are forced through the valve. It is also 55 quite probable that the bubbles of occluded air, or inert gas, as they expand due to the release of pressure, are further subdivided and more uniformly distributed in the mass of shortening.

Under the high pressure maintained in the 60 pump 23 a larger amount of air or inert gas is dissolved in the shortening than would be dissolved at atmospheric pressure and when the pressure is released at the valve 29 the dissolved gas which is in excess of that which will remain 65 in solution at atmospheric pressure, is released in the form of occluded gas. Due to the viscosity of the product, the gas will be released in very small particles which will contribute to the finely dispersed nature of the occluded gas in the shortening.

The shortening then passes to an agitating device generally indicated at C through which it moves at atmospheric pressure. The device may be an open trough or it may be closed. When an 75

open device is used, the fat should preferably cover the agitating paddles for the reason that it is not desirable to incorporate an additional quantity of air into the shortening. As the fat moves through this agitating device, it has a further opportunity to absorb some of the remaining latent heat and a gradual rise in temperature, approaching the packing temperature, takes place. Sufficient time interval is also provided as the shortening moves through this agitating device for the crystalline structure of the fat to become more completely developed and more fully stabilized. During this formation of crystalline structure, as well as during the interval in the unit B, the fat is being continuously agitated so that a rigid network of fat crystals, which would decrease the plasticity of the product, cannot be formed. After the shortening is ready to be packed, there will be a minimum change in the product due to a change in crystalline structure and temperature.

The shortening is next removed by a high pressure pump 31, operated by suitable means such as a motor 32, and forced through a texturizing valve 38 similar to the valve 29. The same operations take place here as have been described in connection with the valve 29. At this time, the shortening is in condition to be placed in containers 34.

Pressure gauges 33 may be inserted at convenient points to determine the pressure to which the fat is being subjected. Similarly, thermometers may be inserted for determining the temperature of the shortening. Recording pressure gauges and thermometers are also desirable to record any variations in temperature or pressure.

The above described apparatus and process may be advantageously combined with a chill roll and picker-box type of operation. It has been pointed out above that in this latter type of operation, the shortening at the conclusion of the beating operation in the picker-box does not have a temperature which approximates tempering temperature. It has also been pointed out that the chilling unit A may be operated so that the shortening will retain sufficient latent heat to raise its temperature above tempering temperature. Therefore, if the chilling unit A is operated in this manner, that portion of the latent heat in excess of that necessary to raise the temperature of the shortening to tempering temperature, will be available for raising the temperature of shortening processed by the chill roll and picker-box type of operation. The shortening from these two processes may be mixed together in a single agitating device, such as the units B or C, prior to packing.

It will be obvious that many forms of apparatus may be used for carrying out the process and therefore it is not intended that the process is to be limited to any particular apparatus. It will also be obvious that many variations in the particular steps and in the order and combination of these steps may be made without departing from the invention defined in the following claims.

We claim:

1. In a method of finishing substantially dry hydrogenated vegetable oil plastic shortening in which the oleaginous material comprising the same in a liquid state is converted into a semi-solid plastic condition, the steps of simultaneously agitating and chilling the material to uniformly and rapidly crystallize at least a portion of the material during the simultaneous agitating and

chilling; terminating the agitating and chilling operation and withdrawing the oleaginous material in a crystallized creamy viscous condition such as would be capable of retaining air and when the resultant latent heat of crystallization available is such as to impart to said oleaginous material a temperature approximating a tempering temperature of the order of 25° to 30° C., and agitating the material in said creamy viscous condition while it acquires said tempering temperature before packaging when the resultant latent heat of crystallization available is at least sufficient to impart to said oleaginous material a temperature approximating a predetermined tempering temperature; withdrawing the oleaginous material in a crystallized creamy viscous condition capable of retaining air; and permitting the material to acquire such predetermined tempering temperature.

2. In a method of finishing substantially dry hydrogenated vegetable oil plastic shortening in which oleaginous material in a liquid state is converted into a semi-solid plastic condition, the steps of introducing a gas into said material; subjecting the material to a chilled surface while agitating the material to uniformly and rapidly crystallize at least a portion of the material during the agitating and chilling; terminating the agitating and chilling operation when the resultant latent heat of crystallization available is at least sufficient to impart to said oleaginous material a temperature approximating a predetermined tempering temperature; withdrawing the oleaginous material in a crystallized creamy viscous condition capable of retaining air; permitting the material to acquire such temperature; and tempering said shortening.

3. In a method of finishing substantially dry hydrogenated vegetable oil plastic shortening in which the oleaginous material comprising the same in a liquid state is converted into a semi-solid plastic condition, the steps of simultaneously agitating and chilling the material under pressure to uniformly and rapidly crystallize at least a portion of the material during the simultaneous agitating and chilling; withdrawing the oleaginous material in a crystallized creamy viscous condition such as would be capable of retaining air; and subsequently treating the material by agitating it while in the creamy viscous condition and texturizing it before packaging; said simultaneous agitating and chilling operation having been terminated when the resultant latent heat of crystallization available in the creamy viscous material such as to impart to said oleaginous material during the said subsequent treatment a temperature approximating a predetermined tempering temperature.

4. In a method of finishing substantially dry hydrogenated vegetable oil plastic shortening in which oleaginous material in a liquid state is converted into a semi-solid plastic condition, the steps of introducing a gas into said material under pressure; agitating and chilling the material under pressure to uniformly and rapidly crystallize at least a portion of the material; said agitating and chilling operation having been terminated when the resultant latent heat of crystallization available is at least sufficient for conditioning said oleaginous material for texturizing and for imparting to it during subsequent treatments a temperature approximating a predetermined tempering temperature; withdrawing the oleaginous material in a crystallized creamy viscous condition capable of retaining air; subsequently

- agitating said material; texturizing the material by placing it under a high pressure and releasing the pressure while passing the material through a small orifice.
5. In a method of finishing substantially dry hydrogenated vegetable oil plastic shortening in which oleaginous material in a liquid state is converted into a semi-solid plastic condition, the steps of gradually pre-cooling the material to 10 the temperature of incipient crystallization to form nuclei crystallizing centers thereby facilitating and improving the rate and nature of the crystallization during chilling; and subsequently simultaneously agitating and chilling the pre-cooled material to uniformly and rapidly crystallize at least a portion of the material during the simultaneous agitating and chilling; terminating the agitating and chilling operation when the resultant latent heat of crystallization available is 15 such as to impart to said oleaginous material a temperature approximating a predetermined tempering temperature; withdrawing the oleaginous material in a crystallized creamy viscous condition such as would be capable of retaining air; and permitting the material to acquire such temperature.
6. In a method of finishing substantially dry hydrogenated vegetable oil plastic shortening in which oleaginous material in a liquid state is converted into a semi-solid plastic condition, the steps of introducing a gas into said material; pre-cooling the material to the temperature of incipient crystallization to form nuclei crystallizing centers; simultaneously agitating and chilling the material to uniformly and rapidly crystallize at least a portion of the material during the agitating and chilling; withdrawing the oleaginous material in a crystallized creamy viscous condition capable of retaining air; subsequently 20 agitating the material; said agitating and chilling operation having been terminated when the resultant latent heat of crystallization available is at least sufficient to impart to said oleaginous material during the subsequent treatment a temperature approximating a predetermined tempering temperature; and tempering said shortening.
7. In a method of finishing substantially dry hydrogenated vegetable oil plastic shortening in which oleaginous material in a liquid state is converted into a semi-solid plastic condition, the steps of introducing a gas into said material; pre-cooling the material by subjecting it to a cooled surface in order to lower the temperature of the material to incipient crystallization to 25 form nuclei crystallizing centers; simultaneously subjecting the material to a chilled surface while agitating the material to uniformly and rapidly crystallize at least a portion of the material during the agitating and chilling; withdrawing the oleaginous material in a crystallized creamy viscous condition capable of retaining air; subsequently 30 agitating the material; agitating the material under a high pressure and releasing the pressure while passing the material through a small orifice; said agitating and chilling operation having been terminated when the resultant latent heat of crystallization available is at least sufficient to impart to said oleaginous material during the subsequent treatment a temperature approximating a predetermined tempering temperature; and tempering said shortening.
8. In a method of finishing substantially dry hydrogenated vegetable oil plastic shortening in which oleaginous material in a liquid state is converted into a semi-solid plastic condition, the steps of introducing a gas into the material while it is in a liquid state and under pressure whereby at least a portion of the gas is dissolved; simultaneously agitating and chilling the material under pressure to uniformly and rapidly crystallize at least a portion of the material during the agitating and chilling; terminating said agitating and chilling operation when the resultant latent heat of crystallization available is at least sufficient to impart to said oleaginous material a temperature approximating a predetermined tempering temperature; withdrawing the oleaginous material in a crystallized creamy viscous condition capable of retaining air and permitting the material to acquire such temperature.
9. In a method of finishing substantially dry hydrogenated vegetable oil plastic shortening in which oleaginous material in a liquid state is converted into a semi-solid plastic condition, the steps of introducing a gas into the material while it is in a liquid state under pressure whereby at least a portion of the gas is dissolved; simultaneously agitating and chilling the material under pressure to uniformly and rapidly crystallize at least a portion of the material during the agitating and chilling; subsequently agitating said material; said agitating and chilling operation having been terminated when the resultant latent heat of crystallization available is at least sufficient to impart to said oleaginous material during the subsequent treatment a temperature approximating a predetermined tempering temperature and withdrawing the oleaginous material in a crystallized creamy viscous condition capable of retaining air.
10. In a method of finishing substantially dry hydrogenated vegetable oil plastic shortening in which oleaginous material in a liquid state is converted into a semi-solid plastic condition, the steps of introducing a gas into the material while it is in a liquid state under pressure whereby at least a portion of the gas is dissolved; simultaneously agitating and chilling the material under pressure to uniformly and rapidly crystallize at least a portion of the material; said agitating and chilling operation having been terminated when the resultant latent heat of crystallization available is at least sufficient for conditioning said oleaginous material for texturizing and for imparting to it during subsequent treatments a temperature approximating a predetermined tempering temperature; withdrawing the oleaginous material in a crystallized creamy viscous condition capable of retaining air; subsequently agitating the material; texturizing the material by placing it under pressure and expanding the same by passing it through a small orifice into a zone of lower pressure; and tempering said shortening.
11. In a method of finishing substantially dry plastic shortening in which oleaginous material in a liquid state is converted into a semi-solid plastic condition, the steps of introducing a gas into the material while it is in a liquid state under pressure whereby at least a portion of the gas is dissolved; pre-cooling the material to the temperature of incipient crystallization to form nuclei crystallizing centers; subjecting the pre-cooled material to a chilled surface while being agitated to uniformly and rapidly crystallize at least a portion of the material during the agitating and chilling; said agitating and chilling operation having been terminated when the resultant latent heat of crystallization available is at least sufficient to impart to said oleaginous material a temperature approximating a predetermined tempering temperature; withdrawing the oleaginous material in a crystallized creamy viscous condition capable of retaining air; subsequently agitating the material; texturizing the material by placing it under pressure and expanding the same by passing it through a small orifice into a zone of lower pressure; and tempering said shortening.

temperature approximating a predetermined tempering temperature and withdrawing the oleaginous material in a crystallized creamy viscous condition capable of retaining air.

5 12. In a method of finishing substantially dry hydrogenated vegetable oil plastic shortening in which oleaginous material in a liquid state is converted into a semi-solid plastic condition, the steps of introducing a gas into the material while 10 it is in a liquid state under pressure whereby at least a portion of the gas is dissolved; pre-cooling the material to the temperature of incipient crystallization to form nuclei crystallizing centers; subjecting the pre-cooled material to a 15 chilled surface while being agitated under pressure to uniformly and rapidly crystallize at least a portion of the material during the agitating and chilling; withdrawing the oleaginous material in a crystallized creamy viscous condition 20 capable of retaining air; subsequently agitating the material; placing the material under pressure and expanding the same by passing it through a small orifice into a zone of low pressure; said agitating and chilling operation having been terminated 25 when the resultant latent heat of crystallization available is at least sufficient to impart to said oleaginous material during the subsequent treatment a temperature approximating a predetermined tempering temperature; and tempering 30 said shortening.

13. In a method of finishing substantially dry hydrogenated vegetable oil plastic shortening in which oleaginous material in a liquid state is converted into a semi-solid plastic condition, the 35 steps which comprise simultaneously agitating and chilling the material to uniformly and rapidly crystallize at least a portion of the material during the agitating and chilling; terminating the agitating and chilling operation when the resultant latent heat of crystallization available is sufficient to impart to such material a temperature higher than a predetermined tempering temperature; withdrawing the oleaginous material in a crystallized creamy viscous condition capable of 40 retaining air; chilling another quantity of the material without agitation; permitting said chilling to continue until the resultant latent heat of 45

crystallization available is insufficient to impart to such material a temperature as high as the predetermined tempering temperature; mixing said materials whereby the excess latent heat of the first referred to material is sufficient to raise 5 the temperature of the last referred material so that the mixed materials will have a temperature approximating the predetermined tempering temperature.

14. In a method of finishing substantially dry hydrogenated vegetable oil plastic shortening in which oleaginous material in a liquid state is converted into a semi-solid plastic condition, the 10 steps of introducing a gas into the material while it is in a liquid condition under pressure whereby 15 at least a portion of said gas is dissolved; pre-cooling a quantity of the material to a temperature of incipient crystallization to form nuclei crystallizing centers; agitating and chilling the precooled material under pressure to uniformly 20 and rapidly crystallize at least a portion of the material during the agitating and chilling; terminating said agitating and chilling operation when the resultant latent heat of crystallization available is sufficient to impart to such material a 25 temperature higher than a predetermined tempering temperature; withdrawing the oleaginous material in a crystallized creamy viscous condition 30 capable of retaining air; chilling another quantity of the material without agitation; permitting said chilling to continue until the resultant latent heat of crystallization available is insufficient to impart to such material a temperature as high as the predetermined tempering 35 temperature; aerating said material; mixing said materials whereby the excess latent heat of the first referred to material is sufficient to raise the temperature of the last referred material so that the mixed materials will have a temperature approximating the predetermined tempering 40 temperature; placing the material under pressure and expanding the material by passing it through a small orifice into a zone of lower pressure; and tempering the material. 45

TRUMAN M. GODFREY.
VICTOR SERBELL.

CERTIFICATE OF CORRECTION.

Patent No. 2,174,364.

September 26, 1939.

TRUMAN M. GODFREY, ET AL.

It is hereby certified that error appears in the printed specification of the above numbered patent requiring correction as follows: Page 6, first column, line 47, for the word "exceed" read excess; line 71, for "picked-box" read picker-box; and second column, line 5, for "exists" read exits; page 7, second column, line 11, claim 1, beginning with the words "when the resultant" strike out all to and including "temperature", line 19, same claim, line 55, claim 3, after "material" insert is; page 8, second column, line 12, claim 8, for "odeaginous" read oleaginous; line 23, claim 9, for "anid" read and; line 60, claim 11, after the word "dry" insert hydrogenated vegetable oil; and that the said Letters Patent should be read with this correction therein that the same may conform to the record of the case in the Patent Office.

Signed and sealed this 24th day of October, A. D. 1939.

(Seal)

Henry Van Arsdale,
Acting Commissioner of Patents.
